UNITED STATES PATENT OFFICE.

FREDRICK LARSEN, OF SKANDIA, MICHIGAN.

TIMBER-FEEDER FOR SAWMILLS.

1,219,649.

Specification of Letters Patent. Patented Mar. 20, 1917.

Application filed April 17, 1914. Serial No. 832,445.

To all whom it may concern:

Be it known that I, FREDRICK LARSEN, a citizen of the United States, residing at Skandia, in the county of Marquette and State of Michigan, have invented certain new and useful Improvements in Timber-Feeders for Sawmills, of which the following is a specification.

This invention relates to timber feeders for saw mills. The object of the invention is to provide such a device comprising a frame provided with track upon which a forwardly and backwardly movable carriage is provided which carriage is connected by a lever-controlled feed device and equalizer with said frame and through the medium of which device the timber to be cut is prevented from turning or moving independently of the carriage during the sawing operation which movement, otherwise, would cause binding stress upon the saw; another object is to prevent irregular movement of the carriage during the sawing operation.

With the foregoing and other objects in view the invention consists in the combination and arrangement of parts to be hereinafter fully described in the following specification, pointed out in the appended claim and illustrated in the accompanying drawings which form a part of said specification and in which—

Figure 1 is a front elevation of my improved machine.

Fig. 2 is an end view taken at the front end of the machine on line 2—2 of Fig. 1.

Fig. 3 is a cross section taken on line 3—3 of Fig. 1.

Fig. 4 is a plan of the saw carriage.

Fig. 5 is a plan of the carriage-supporting means including the feed device and equalizer.

Figs. 6, 7, 8, 9, 10 are enlarged detail views of portions of the feed device and equalizer.

Like reference characters indicate corresponding parts throughout the several views.

The frame of my device comprises a plurality of supporting posts or standards 1 fixed to brace ties 2 and connected by longitudinally extending rails 3; said standards are further connected in pairs by transversely extending braces 4 which are formed with semi-circular centrally dis-

posed grooves adapted to receive a longitudinal tube 5 which is further secured in position against lateral movement, but capable of rotary movement, by yokes 6 also grooved to fit said tube and which are connected to the braces 4 by bolts 7. To the upper ends of the standards 1 transversely extended rails 8, disposed in the plane of the brace ties 2, are fixed which carry narrow gage track 9, 9 and broad gage track 65 10 and upon said track the log carriage is movably disposed which comprises a pair of longitudinally extending beams 11, 11 connected by the truck pieces 12, 13, 14; the truck pieces 12 and 14 being provided 70 with grooved wheels 15 and the truck piece 13 being provided with flat wheels 16 adapted to run upon the tracks previously described.

The log carriage is further provided with 75 a plurality of log stops 17 connected by braces 18 to the beams 11 and with rolls 19 bolted as at 20 to said beams 11. The front end of my saw carriage is provided with the bifurcated standard 21 in which 80 the log retaining lever 22 is pivoted.

In Figs. 1 and 2 the log carriage is shown disposed upon and operatively connected to the frame. One or more logs are manually placed upon the rollers 19 of the carriage 85 and extend longitudinally of the same to be cut by the saw (not shown) which is disposed immediately in advance of the front end of the carriage and frame which is indicated by the line 2—2 of Fig. 1. 90

To the truck pieces 12, 13, 14 of the log carriage I secure draw blocks 23 which blocks carry the draw bars 24 that are connected by arms 25 with the tube 5; said arms being provided with the sectional 95 clamps 26 which partially encircle said tube and said arm 25 further is formed with a shoulder 27 square in cross section and fitted into a square opening in the tube to prevent rotation of said arm.

The tube 5 is rotated in its supports by means of curved arm 25^a, secured to the pipe in a manner similar to the arm 25 that engages a pitman 28 connected to a hand lever 29 which is pivotally disposed upon 105 a pin 30 that connects a pair of parallel supports 31, 31 connected to the rails 3 and to said supports an angle iron 32 is secured, the upper or free end of which is adapted to serve as a stop for the arm 25^a as the 110

lever 29 is moved in one direction and as a stop for the pitman 28 as this lever is moved in the opposite direction.

The log to be cut is manually fed beyond the front end of the carriage as desired to permit its engagement by the saw and then locked in this position by the log retaining lever 22. The carriage with the log in locked position is now moved toward the saw by means of the lever 29 which is raised or moved from the position shown in Fig. 2 to the position shown in Fig. 3, thus causing partial rotation of the tube 5 through the medium of the pitman 28 and arm 25^a and, further, causing the arm 25 and draw bar 24 to impel the saw carriage toward the saw or in the direction of the log stops 17. This movement can be effected gradually as the saw penetrates the log and the several arms 25 and draw bars 24 connecting the carriage and tube 5 insure regular movement of said carriage and of the log carried thereby, the stop or angle iron 32

effectually preventing movement of the carriage beyond its frame in either direction. 25

What is claimed is:—

In a timber feeder for saw mills, a frame, a movable carriage, actuating means for said carriage carried by said frame, said means including a curved arm and a pitman connected thereto, and a stop iron carried by said frame and having its free extremity disposed in the plane of movement of said actuating means for engagement with said curved arm as the carriage moves in one direction and for engagement with said pitman as the carriage moves in the opposite direction. 30 35

In testimony that I claim the foregoing as my own I have hereto affixed my signature in the presence of two subscribing witnesses. 40

FREDRICK LARSEN.
